UNITED STATES PATENT OFFICE.

CHARLES B. DAVIS, OF NEW YORK, N. Y.

MASH-TUN OR THE LIKE.

1,201,268.

Specification of Letters Patent. Patented Oct. 17, 1916.

Application filed January 2, 1915. Serial No. 5.

To all whom it may concern:

Be it known that I, CHARLES B. DAVIS, a citizen of the United States, residing at New York, in the county of New York and State of New York, have invented certain new and useful Improvements in Mash-Tuns or the like, of which the following is a specification.

This invention relates to improvements in mash-tuns or the like, and one of the objects of the invention is to provide a mash-tun for straining the extract from the spent grains or husks without danger of clogging.

Another object of the invention is to provide an apparatus attaining the object above referred to which is very simple and economical to manufacture and which, on account of its simplicity, is not apt to get out of order.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as a part of this specification, and in which I have shown a merely preferred form of embodiment of the invention, Figure 1 is a vertical section illustrating a mash-tun having its bottom fitted with my improved sieve-means; Fig. 2 is a fragmentary plan of a portion of the double bottom or sieves; Fig. 3 is a view similar to Fig. 2 but showing the sieves in a different relation; Fig. 4 is a diagram illustrating the course of the liquid in its passage from the interior of the tun to the exterior thereof through the sieve, and Fig. 5 is a vertical sectional view through another form of sieve or bottom.

Referring to the numerals on the drawing, 6 represents a receptacle or tun of the sort which may be employed in the brewing or distilling arts, adapted to receive the grains and water or other liquid, and wherein in the mashing operation is adapted to take place.

7 represents the bottom of the tun or receptacle, which is interiorly provided with annular steps 8, 9 and 10, the last constituting the actual inside bottom of the tun.

The tun is also provided with what may be termed a false bottom, comprising in Figs. 1, 2 and 3, a pair of superposed plate-members 11 and 12, the member 11 being supported on the step 9, and upon the ribs 14 which project upwardly from the step or bottom 10, and the plate 12 overlying the plate 11 and resting upon the same and upon the step 8. In the form shown in Figs. 1, 65 2 and 3, these two plates 11 and 12 have openings 15 and 16 formed therein, which openings are arranged so that they can be made to register or not to register in accordance with the direction of reciprocation 70 of an actuating rod 17 which extends through a stuffing box 18 in the side of the tun's bottom 7. It is not intended ordinarily that the respective openings in the two plates 11 and 12 shall be brought into 75 registry. Normally, they are left out of registry and the filtration of the liquid contents of the tuns takes place because of the fact that the two plates are not in absolute water-tight contact. The consequence is 80 that the liquid may enter the apertures 15 in the plate 12, whence it passes as a film between the opposed faces of the two plates, and thence out through the apertures 16 in the plate 11. This tortuous path is indicated by the diagram in Fig. 4. While the liquid may thus escape through the false bottom, the plates are so close together as to prevent the escape of even very small particles of solid matter, and clogging is 85 avoided. Furthermore, I prefer that the openings in the upper plate, indicated at 15, shall be elongated as shown, wider than the width of the average barley malt or other grain used in the mashing process, and narrower than the length of such grain. The result of this particular arrangement is that though grains may lodge in the openings 15, they cannot, on account of the closeness of the plates, pass between the plates, 90 and furthermore they will be washed out of the openings 15 on account of the agitation of the contents of the tun which accompanies the mashing operation.

When it is desired to filter the contents of 105 the tun, the agitation is stopped and a valve 19 in the bottom of the tun is opened, whereupon the grains, on account of the particular size and shape of the openings 15, straddle these openings and form a sort of mat, 110 through which the liquid passes from the tun and out through the pipe 20.

I conceive one of the important features of my invention to be the provision of a tun-bottom having plate-like members in superposed relation, and almost in water-tight contact with the spaces between the plates opening both to the interior and the exterior of the tun, so that the liquid contents of the tun may escape between the plates in a sort of film, while the escape of solid particles is prevented.

Another characteristic of the invention is in the size and shape of the openings in the upper plate, as described.

When it is desired to open the bottom more fully for the escape of liquid or any other purpose, the openings 15 and 16 may be brought into registry by manipulating the rod 17.

As a modification of the invention, and as illustrating the scope of protection which I have in mind, I show in Fig. 5, in place of two superposed plates 11 and 12, a plurality of over-lapping plate-members 21. These plate-members, also, supported in any desired way, and positively connected together if necessary by means of spot-welding or rivets arranged at intervals, are close enough together to prevent the passage of solid particles between them, while, at the same time, they permit of the escape of liquid between adjacent plates in a film, and the path of the liquid from the interior to the exterior of the tun through the sort of bottom shown in Fig. 5 is also indicated by the diagram of Fig. 4. In both forms of the device, that is, the one shown in Fig. 1 and the one shown in Fig. 5, the liquid takes a tortuous path, which includes intermediate its ends a portion defined between plate-members which are in close but not water-tight contact. And in both forms the tendency of the solid matter is not directly downward. Thus clogging is further minimized. To put the matter in another way, in each form of the invention the actual straining takes place in horizontal directions, instead of in vertical directions as is the case in all prior devices with which I am familiar.

Inasmuch as many changes could be made in the above construction, and many apparently widely different embodiments of my invention could be made without departing from the scope thereof, it is intended that all matter contained in the above description or shown in the accompanying draw-

ings shall be interpreted as illustrative and not in a limiting sense. It is also to be understood that the language used in the following claims is intended to cover all the generic and specific features of the invention herein described and all statements of the scope of the invention which, as a matter of language, might be said to fall therebetween.

It should be noted that the present application is in part a continuation of my application Serial No. 714,565, filed August 12th, 1912, for brewing apparatus, &c., which application I propose to abandon as soon as the present one is of record.

I claim:

1. A mash-tun or the like having a bottom comprising two plate-like members in superposed relation, said plate-like members being close enough together to substantially prevent the entrance or passage of solid particles between them, but being out of water-tight contact, so that liquid may enter and pass between them in a film, 75 one of the plate-like members having an opening therein which communicates with the interior of the tun, and the other plate-like member having an opening therein which communicates with the exterior of 80 the tun, said openings being out of registry, the opening in the plate-like member which is in communication with the interior of the tun being wider than the width of the average barley malt grain and narrower 85 than the length of such grain.

2. A mash-tun or the like having a bottom comprising plates in superposed relation and horizontally disposed, the plates being close enough together to substantially 90 prevent the entrance and passage between them of solid particles, but out of water-tight contact, so that liquid may enter and pass between them in a film, the upper plate having a plurality of apertures therein, and the lower plate having a plurality of 95 apertures therein, said apertures being out of registry, the openings in the upper plate being wider than the width of the average barley malt grain and narrower than the 100 length of such grain.

In testimony whereof I affix my signature in presence of two witnesses.

CHARLES B. DAVIS.
